UNITED STATES PATENT OFFICE.

HUGO STEARNS, OF FREEPORT, NEW YORK.

MILLINERY-DISPLAY DEVICE.

1,302,987.

Specification of Letters Patent.

Patented May 6, 1919.

Application filed December 11, 1918. Serial No. 266,228.

To all whom it may concern:

Be it known that I, HUGO STEARNS, a citizen of the United States, and a resident of Freeport, in the county of Nassau and State 5 of New York, have invented a new and Improved Millinery-Display Device, of which the following is a full, clear, and exact description.

This invention relates to display devices 10 and has particular reference to means for displaying hat trimmings, such as feathers or the like, or other commodities of a merchantable character.

Among the objects of the invention is to 15 provide a holder which may partake of the character of a box or analogous receptacle to constitute a cover or closure means for the commodities, said holder being provided with means for suitably holding individual 20 millinery units or the like.

Another object of the invention is to provide a display device for plumes, said device comprising a base supporting a cell structure adapted to receive and hold a plurality of individual plumes, the cell structure being so designed and fixed in place 25 upon the base or main holder as to keep the plumes in fixed position separating them from one another, and also to produce the 30 best possible display.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like 35 reference characters designate the same parts in the several views, and in which—

Figure 1 is a vertical transverse sectional view on the line 1—1 of Fig. 2;

Fig. 2 is a plan view of the structure complete with the cover omitted and showing only a part of the cells occupied with plumes; and

Fig. 3 is a sectional detail on the line 3—3 of Fig. 2.

50 In carrying out my invention in a form that has been found in my practice to be exceedingly attractive and substantial, I employ a box or carton comprising a base member 10 having a relatively shallow marginal flange 11, and also a cover member 12

adapted as shown to telescope within the flange 11 and having a depth materially greater than that of the flange so as to provide ample interior space for the goods to be carried and displayed therein and thereby. It must be understood that in the handling and displaying of millinery or analogous devices a set of four, six, or any other suitable number of plumes P are adapted to be packed, shipped, or displayed 60 in a group by the means substantially as illustrated. By such means the plumes are held by their stems in a form or position most suitable for their protection as well as for the best possible display purposes. Being 65 presented in a group it follows, for example, that all of the members of the group are displayed at the same time in the most advantageous position and the effect on the trade is particularly pleasing, and hence advanta- 70 geous to the dealer. Not only is each plume well displayed when held by the means indicated, but the group effect adds to the esthetic result.

At or about the center of the base 10 and secured upon its inner surface is a cell structure formed of a strip of some suitable relatively firm but bendable sheet material such as strawboard, or its equivalent, and indicated as a whole at 13. The width of the strip 80 of sheet material from which this structure is formed is slightly less than the height of the cover member 12, and the length of such strip is sufficient to form the desired number of arc shaped vertical cells 13', shown as six 85 in number in this case. Said strip is folded upon itself along vertical bending lines 14 of which there are shown five in this instance all equally spaced from one another and the extreme ends 15 of the strip which are 90 brought together and fastened by a rivet 16, or its equivalent, a similar fastening device being employed at each folded portion of the strip. At or adjacent to each joint or folded portion of the cell device is a foot 17 100 formed preferably as an integral part of the sheet structure and bent at right angles to the joint portion thereof so as to lie flat against the inner surface of the base 10. Suitable permanent fasteners such as rivets 105 18 are employed to pass through these feet and the base whereby the feet are locked to the base and the entire cell structure is held in fixed firm position. The concave curvature of each cell 13' is directly adapted for 110

supporting the rounded body portion of a plume as will be appreciated in comparing the right sides of Figs. 1 and 2.

Spaced radially outward between each cell and the margin of the base 10 is a keeper 19 consisting of a strip of sheet material such as strawboard of a somewhat heavier character than that composing the cell structure, the longer axis of the keeper 19 being preferably parallel to the chord connecting the two ends of each cell. In other words the keeper is arranged perpendicular to that radius of the base which passes through the center of curvature of the cell to which said keeper applies. Each keeper is fixed to the base by any suitable means such as rivets 20 on the opposite sides of its center whereby there is provided a loop or slight vertical space between the inner surface of the base 20 and the center of the keeper and into which the stem S of a plume is adapted to be slipped directly in a direction outward from the center of the base 10. In other words the operator or dealer putting the plume in place in its cell will grasp the same just above the end of the stem and will then cause the end or point of the stem to pass directly between the inner edge of the keeper and the base, the rounded portion of the plume at such time sweeping easily downward into and along the cell 18' therefor. The side or flowing portions of the plume will thus be gently but sufficiently firmly embraced by the side portions of the cell and so the plume 35 as a whole will be held in fixed position for shipping or display purposes. The group of plumes or the like so supported for display on the base and the cover 12 put in place a reliable shipping package is produced, assuring that the millinery therein will be carried in safe condition and always ready for immediate display when the cover is removed.

I claim:

45 1. The herein described display device for plumes comprising a base, a cell structure fixed adjacent to the center of the base and providing a series of independent cell

spaces to individually receive and hold the curved body portions of a series of plumes 50 properly spaced from one another in a circular disposition, and a keeper spaced radially outward from each cell space for holding the stem of the plume held in such cell space, whereby the main portions of all of 55 the plumes are grouped near the center of the display device.

2. In a display device for millinery, the combination of a base, a cell structure composed of a strip of sheet material folded 60 upon itself at a plurality of places spaced equally from one another and from the ends of the strip, means rigidly fixing the otherwise free ends of the strip directly together, means fastening the adjacent portions of the 65 cell structure together adjacent to the holding lines aforesaid, said fastening means serving to cause the several cell elements to assume concave forms to receive individual millinery units, and means spaced radially 70 outward from the several cells to lock said millinery units in the several cells, substantially as set forth.

3. The herein described shipping and displaying device for millinery comprising a 75 base having a shallow marginal flange, a cover member telescopically connected to said flange and having a depth materially greater than the flange, a cell structure formed of sheet material arranged centrally 80 within the space between the base and the cover, said cell structure including a plurality of concave cell units for receiving and holding a like number of millinery units, means to lock the cell structure to one of the first mentioned parts, said means including a plurality of feet formed integral with the cell structure and fastening devices passing through the feet and the part to which the cell structure is attached, and 85 keeper means fixed to the part to which the cell structure is connected and located radially outward from the several cells thereof to lock the millinery units in their respective cells.

HUGO STEARNS.
